UNITED STATES PATENT OFFICE.

WILFRID SALMON, OF ST. PAUL, MINNESOTA.

RAILWAY CAR DOOR.

1,415,484.

Specification of Letters Patent. Patented May 9, 1922.

Application filed February 26, 1920. Serial No. 361,370.

To all whom it may concern:

Be it known that I, WILFRID SALMON; a citizen of the United States, and a resident of St. Paul, in the county of Ramsey and 5 State of Minnesota, have invented certain new and useful Improvements in Railway Car Doors, of which the following is a specification.

My invention relates to improvements in 10 car doors, and it consists in the constructions, combinations and arrangements herein described and claimed.

One of the foremost objects of the invention is to provide a car door which can 15 be fitted into the door opening with varying degrees of tightness, ranging from a relatively loose fit for purposes of ventilation, to a very tight fit, which practically seals the door in the opening.

20 A further object of the invention is to provide an arrangement of castings which are used in connection with the improved car door, which castings can be operatively applied to any size door and door opening, and regardless of whether the car to 25 which they are to be applied is old or new.

Other objects and advantages will appear in the following specification, reference being had to the accompanying drawings, in which:

Figure 1 is a side elevation of the improved car door, showing it in position over a door opening.

Figure 2 is a side elevation of a part of 35 a side of a car, the door being removed in order to illustrate the positions of the various brackets and castings referred to below.

Figure 3 is a vertical section taken substantially on the line 3—3 of Figure 2.

40 Figure 4 is a detail sectional view taken substantially on the line 4—4 of Figure 1, illustrating the door in an open or ventilating position.

Figure 5 is a similar view showing the 45 door in the tightly closed position.

Figure 6 is an elevation of the inside of the improved car door.

Figures 7 and 8 are detail views of the operating or closure lever,

50 Figure 9 is a detail elevation of one of the wheel housings carried by the door.

Figure 10 is a detail perspective view of the right sill casting.

Figure 11 is a detail perspective view of 55 one of the roof brackets, and

Figure 12 is a detail perspective view

of one of the thimbles for spacing the upper rail from the side of the car.

By reference to the drawings it will be observed that the lower rail 1 is supported 60 adjacent to the car door opening 2 by means of the left and right sill castings 3 and as many additional supports 4 as may be required. The rail wheels 5 run on the rail 1, and being carried by the door 6 support 65 the whole weight of the door and its carried parts.

There is a wheel housing 7 in each lower corner of the door 6, these wheel housings being properly arranged to accommodate 70 the rail wheels 5, the wheels themselves being suitably mounted at 8. An extension 9 from the outer corner of each wheel housing 7 is made into the shape of a hollow housing to provide a cover for the extending 75 flanges 10 of slides 11 in slide brackets or castings 12.

When the car door is opened, that is to say spaced away from the door opening 2 in Figure 4, the bracket cover 9 of course 80 stands quite a distance from the flanges 10. But when the closure lever 13 on the outside of the car, is manipulated to cause the closure wheels 14 to ride down the inclined slides 11 in the castings 12, then the door 85 has moved inwardly into the opening and the flanges 10 are completely covered as indicated in dotted lines in Figure 5, so that they may be neither seen from the outside nor can access be had to the operating 90 mechanism.

The sill castings 3, of which there is one at each lower corner of the door opening as indicated in Figure 2, are made right and left handed so that the track 15 formed on 95 top of each, may come next to the jamb of the door opening. Guide wheels 16 run upon these tracks when the door 6 is moved from the position in Figure 4 to that in Figure 5, at which time the rail wheels 5 100 are displaced from the rail 1, as clearly indicated in Figure 5.

A depression 17 in each sill casting 3, makes room for the flange of the rail wheel 5 when the wheel is displaced as just stated. 105 In other words, under normal conditions, the rail wheels 5 run on the rail 1, but when the car door 6 is moved inwardly so as to tightly close the opening 2, the rail wheels are lifted off of the rail 1 and moved 110 inwardly with the door. Under such circumstances it is necessary to properly support

the door, and it is the guide wheels 16 which perform the supporting function of the door.

In the top corners of the door opening 2 there are other slide brackets 18 very much 5 on the order of the slide brackets 12, in that they too are provided with inclined slides 19 upon which closure wheels 20 ride. Figure 6 shows the inside construction of the car door. Here the various closure wheels 10 14 and 20 are shown mounted on closure links 21 and 22 which are suitably pivoted on supports 23.

The ends of these links are connected by rods 24, other rods 25 running from the bottom link to an inside lever 26, at the pivotal point 27 to which the outer closure lever 15 13 is connected.

Normally the closure lever 13 hangs down about as shown in Figure 1, at which time 20 it abuts the stop 28 on the bracket 29 which provides the pivotal support of the lever as clearly shown in Figure 8. Upon raising the closure lever 13 into engagement with the notches of the circular rack plate 30, the 25 various links, rods and levers on the inside of the door in Figure 6 are moved on their pivotal points so that the closure wheels 14 and 20 are caused to ride down the various inclined slides 11 and 19 and thus cause 30 the door to move inwardly as already fully explained in connection with Figure 5.

The end 31 of the closure lever has an aperture 32 for the purpose of affixing a suitable seal after the lever has been moved 35 to the final position over the rack 30. To this end the rack may have a plurality of apertures through any one of which the sealing wire may be threaded in connection with the aperture 32. A broken seal wire will of 40 course indicate that the car door mechanism has been tampered with.

There is a bracket cover 33 for each of 45 the slide brackets 18, it being observed that these bracket covers conceal or house the closure wheels on the ends of the closure links. The provision of these covers therefore makes the closure wheels inaccessible from the outside. These covers are parts of castings 34 which are suitably affixed to 50 the door 6 at the top.

The top of the door 6 is unsupported but is prevented from falling outwardly by the rail 35 which is mounted on suitably disposed rail brackets 36, one of which is shown 55 in detail in Figure 11. A number of intermediate thimbles 37 keep the upper rail 35 in proper spaced relationship to the side of the car. The top of the brackets 36 are inclined and further provided with lugs 38 60 through which the roof 39 is secured. The roof excludes moisture from the door, and as the door is slid back and forth over the bottom rail 1, the upper end merely glides 65 against the rail 35, there being no occasion for any other arrangement.

A bumper 40 limits the opening movement of the door 6. The door is held in the open position by means of a latch 41 pivoted on a casting 42, which casting is provided with stops 43 between which the latch operates. 70 A keeper 44, suitably cast inside of the right housing 7, is intended to be engaged by the latch 41 to hold the door in the open position.

The operation may be briefly reviewed to 75 advantage. Ordinarily the rail wheels 5 of the car door 6 run on the rail 1 at the bottom. When thus positioned, the door may be moved back and forth to the open and closed positions.

When it is intended to close the door in the opening 2, the door is moved along into alignment with the opening at which time the closure wheels 14 and 20 come into alignment with the flanges of the various inclined slides at the top and bottom in readiness for the closing movement. The closure lever 13 on the outside is now lifted until the projection 31 engages the lowermost of the teeth of the rack plate 30. The door may be 80 closed to a greater or less degree, that is to say, if the closure lever is moved up but a short distance, a ventilating space will remain around the door 6 by reason of the fact that at such time the door is not fully 85 closed.

But the door may be tightly sealed in the opening 2 as shown in Figure 5. This is accomplished by moving the closure lever 13 over the full extent of the rack 30, this 100 operation causing the various wheels 14 and 20 to ride further down the inclines 11 and 19 so that the door becomes tightly wedged in the opening. The rail wheels 5 are lifted from the track 1 during the first part of the 105 movement of the closure lever 13 over the rack 30.

But the weight of the door and its carried parts is then sustained by the guide wheels 16 which come into engagement with the 110 track 15 of the sill casting, further movement of the closure lever 13 causing the door 6 to move inwardly as explained, and at the same time causing the guide wheels 16 to ride inwardly over the track as stated. As 115 pointed out in the objects of the invention the various castings may be applied to either old or new doors, and the size of the door or door opening is immaterial because these castings can be applied to any size door. 120 One great advantage rising from the embodiment of the invention in a car door, exists in the ability to make either a loose door connection for purposes of ventilation, or a very tight door connection which practically seals the door in the opening and excludes the entrance of air.

While the construction and arrangement of the improved car door as herein described and claimed, is that of a generally preferred 125 130

form, obviously modifications and changes can be made without departing from the spirit of the invention or the scope of the claims.

5 I claim:—

1. In combination with a car having a door opening and a rail, of a door with wheels running on the rail, means carried by the door operating with a lever action
- 10 for bodily lifting the door and wheels from the rail into the opening, means located in the opening with which said lever mechanism cooperates in performing the lifting action, and means carried by the door and
- 15 cooperating means located in the door opening providing a support for said door as it is conveyed from the rail into the opening.
2. The combination of slide means suitably fixed in each corner of a car door opening, and a car door, with lever mechanism coacting with the slide means to transport the door into the opening, and means operative in the closed position of the door for covering each otherwise exposed part of the
- 25 slide means and lever mechanism, to prevent access from the outside.
3. The combination of castings suitably fixed in each corner of a car door opening, each with inclined slides; and a car door
- 30 with lever mechanism on the inside and actuating means therefor on the outside, including means arranged to move down the slides and thereby lift the door into the opening, and means carried by the door covering the otherwise exposed part of the casting and lever mechanism when the door is closed.
4. A car door, with a link pivoted substantially in each corner, all so connected
- 40 as to be simultaneously rocked by an externally accessible closure lever; castings having slides with which the pivoted links operate in combination, suitably mounted in the corners of a door opening; a housing
- 45 on each lower door corner, containing rail wheels and guide wheels to run on appropriate tracks on the sill of the door opening when the door is carried therein, said housing including portions covering the exposed operating ends of the adjacent links; and similar covers for the exposed ends of the upper links, all covers concealing the adjacent parts of the aforesaid slides when the door is closed.
- 55 5. The combination of sill castings with track portions, mounted in each corner of the sill of a door opening, and a car door, with wheels normally running on a rail, arranged to be lifted from the rail into the
- 60 door opening and provided with guide wheels then running on the track portions.

6. The combination of sill castings in-

cluding tracks and depressions, mounted on the sill in the corners of a door opening; a rail affixed to extended parts of said castings, and a car door with rail wheels normally running on the rail, including means for lifting the door and rail wheels from the rail into the opening, at which time said wheels occupy the depressions, and guide 70 wheels on the door running on the track when the rail wheels are lifted from the rail.

7. In combination with a car having a rail, a car door having housings with wheels 75 mounted therein and running on the rail, one housing including a lug; and a latch, operating between stop lugs on a casting affixed to the car, arranged to engage the lug when the door is drawn back there- 80 against.

8. In combination with a car having a rail, a car door having housings with wheels mounted therein and running on the rail, one housing including a lug; a latch, operating between stop lugs on a casting affixed to the car, arranged to engage the lug when the door is drawn back thereagainst, and a bumper on the car for limiting the backward movement of the door. 90

9. In combination with a car having a door opening and a rail, of a door with wheels running on the rail, and guide wheels arranged to run on tracks on sill castings located in the corners of the opening; 95 castings in the four corners of the opening with slides, a pivoted lever mechanism on the inside of the door, including links with end rollers to ride in the slides, and an external closure lever by which said mechanism is operated; closure means located substantially in the corners of the door covering the rollers and otherwise exposed parts of the aforesaid castings, the lower closure means being parts of housings containing the rail wheels and guide wheels; a roof over the door on brackets to which an upper rail is affixed to support the otherwise loose upper end of the door; and a rack plate co-operating with the closure lever enabling 100 varying degrees of closure of the door in the door opening by moving the lever through various distances over the rack plate. 105

10. In combination with a car having an opening, a door movable on a track into position opposite the opening, means both assisting to support the track and adapted to support the door when off the track, means to lift the door off the track and laterally into the opening, and means carried 110 by the door adapted to then engage said supporting means to support the door while off the track. 120

WILFRID SALMON.
